US00D714941S

(12) **United States Design Patent**
Kim

(10) **Patent No.:** **US D714,941 S**
(45) **Date of Patent:** **** Oct. 7, 2014**

(54) **STAND FOR X-RAY IMAGING APPARATUS**

(71) Applicant: **Nanofocusray Co., Ltd.**, Jeollabuk-do (KR)

(72) Inventor: **Kyong Woo Kim**, Jeollabuk-do (KR)

(73) Assignee: **Nanofocusray Co., Ltd.**, Jeollabuk-do (KR)

(**) Term: **14 Years**

(21) Appl. No.: **29/482,509**

(22) Filed: **Feb. 19, 2014**

(30) **Foreign Application Priority Data**

Jan. 6, 2014 (KR) 30-2014-0000610

(51) **LOC (10) Cl.** **24-01**

(52) **U.S. Cl.**

USPC **D24/158**

(58) **Field of Classification Search**

USPC D24/158-161, 185, 186; 378/4, 21-27, 378/38, 40, 102, 196-198; 248/125.1, 127, 248/158

(57) **CLAIM**

I claim the ornamental design for stand for X-ray imaging apparatus, as shown and described.

DESCRIPTION

FIG. 1 is a perspective view of stand for X-ray imaging apparatus showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

1 Claim, 7 Drawing Sheets
